UNITED STATES PATENT OFFICE.

EDWIN C. JORDAN, OF JORDAN SPRINGS, VIRGINIA.

MAIL-BAG.

SPECIFICATION forming part of Letters Patent No. 639,581, dated December 19, 1899.

Application filed September 25, 1899. Serial No. 731,621. (No model.)

To all whom it may concern:

Be it known that I, EDWIN C. JORDAN, a citizen of the United States, residing at Jordan Springs, in the county of Frederick and State 5 of Virginia, have invented new and useful Improvements in Mail-Bags, of which the following is a specification.

My invention relates to certain new and useful improvements in mail-bags.

10 It is the object of my invention to provide a mail-bag which may be readily and securely locked and unlocked and which shall be simple and durable in construction and of the minimum weight.

15 To this end the invention consists in the features of construction and combination of parts hereinafter described, and particularly pointed out in the claims.

I have illustrated my invention in the accompanying drawings, in which—

Figure 1 is a perspective view with the mouth of the bag shown extended or opened. Fig. 2 is a sectional plan showing the mouth of the bag closed, and Fig. 3 is a transverse

25 vertical section taken on the line 3 3 of Fig. 2.

Referring to the drawings, the numeral 1 indicates what I will term the "front" side of the bag, and 2 the "rear" side. Said rear side has a projecting portion extending beyond the 30 edge of the front side to form a flap 3 for closing over the mouth of the bag, as usual. On the rear or outer side of this flap and centrally thereof I secure by rivets a relatively long metal plate 4, to which is secured a staple 5, 35 which projects from the front of said flap, and is further secured on said front side by having its prongs extend through a metal plate 6, also riveted to the body of said flap. At opposite corners of the bag I secure by

40 rivets two ordinary butt-hinges, respectively, 7 and 8, the leaves whereof extend inward and the upper edges of which lie flush with the upper edge of the front side of the bag. Secured to the inner side of each leaf of these

45 hinges is a metal plate, these plates being denoted, respectively, by the numerals 9, 10, 11, and 12. The said plates extend from the corners of the bag to points some distance removed from the center of each side, so as to 50 leave a flexible portion of the bag between the inner ends of each pair of plates, which arrangement permits the plates to be opened

outward on their hinges. The construction is such that when the two sets of plates are separated to open the bag the mouth of the bag will be held distended, so that mail-matter may be readily thrown into the bag. The rivets which secure these plates to the leaves of the hinges will, in practice, be continued through the material of the bag to also secure 60 the leaves of said hinges to the sides of the bag, so that one set of rivets secures the plates to the leaves of the hinges and the hinges to the sides of the bag. These plates extend along the upper edge of the bag, as shown, 65 and are riveted thereto at intervals along their length, as indicated by the numerals 13. The plates 9 and 10 are those secured along the inner side of the rear side of the bag, and in the space between their ends I secure by rivets a pad of thick leather or other relatively 70 hard but flexible material 14, which pad projects beyond the surface of the plates 9 and 10 in such manner that when the opposite sides of the bag are brought together the pad 75 will fit in the space between the inner ends of the plates 11 and 12, secured on the inner side of the front side of the bag. Extending from opposite sides of the bottom portion of the pad 14 and lying along the underedges of the plates 80 9 and 10 are two relatively thick straps or projections 15, which also project beyond the inner faces of the plates 9 and 10 and, in fact, form continuations of the pad 14. The purpose of these straps is to lie beneath the under edges 85 of the plates 11 and 12 when the bag is closed, so as to close any space left between the plates 9, 10 and 11, 12 and prevent letters from passing upward between said plates, where they might be extracted by an ingenious person. The pad 14 by filling up the space between the ends of the plates 11 and 12 serves a similar function in addition to that of forming a bearing-surface for the material of the front side of the bag to bear against when the 90 bag is closed. On the outer side of the front side of the bag and in the space between the ends of the plates 11 and 12 I secure a metal plate 16, having a rectangular opening 17, which opening is also extended through the 100 material of the bag. In like manner the pad 14 is provided with an opening 18, which is also continued through the material of the bag. In locking the bag the two sets of plates

are brought together, the flap 3 turned over the mouth of the bag, and the staple 5 passed through the openings 17 and 18, when a lock may be secured in said staple at the back of 5 the bag. It is obvious that the plates 9, 10, 11, and 12 may themselves form the leaves of the two hinges 7 and 8; but I prefer to secure these plates on the inner sides of the leaves of the hinges, as described, so that when the 10 hinges are closed the two sets of plates will be brought close together, as will be understood.

It will be seen that with my construction the bag can be quickly unlocked and opened 15 and as quickly closed and locked in almost a single movement for either operation. It will be further seen that when closed and locked the pad 14 and straps or projections 15 will prevent the letters from working upward to 20 the mouth of the bag, and thus the extraction of mail-matter from the bag is rendered impossible.

I may provide a leather or other handle 19 for carrying the bag, which may be riveted 25 thereto, as usual.

I have shown the pad 14 in Fig. 1 as being of less thickness than straps or projections 15, the purpose of this being to permit the plates at the top of the bag to be pulled together 30 firmly when the bag is locked. I do not wish, however, to limit my invention to any special degree of thickness of the pad 14 relative to the straps or projections 15.

Having thus fully described my invention, 35 what I claim as new is—

1. A mail-bag having a hinge secured in each corner at the mouth of the bag, metal

plates secured to the leaves of said hinges and to the material of said bag and extending, respectively, to points removed from the center of the bag, whereby to leave a flexible portion between the inner ends of said plates to serve as a hinge, and a pad secured to one side of the bag in the space between but unconnected with the ends of the plates on that 45 side and adapted to be received in the space between the ends of the plates on the opposite side, substantially as described.

2. A mail-bag having a hinge secured in each corner at the mouth of the bag, metal 50 plates secured to each leaf of the hinges and extending along and secured to the body of the bag, and terminating, respectively, at points removed from the center of the bag, whereby to leave a flexible portion between 55 the inner ends of said plates, a pad secured to one side of the bag in the space between the ends of the plates on that side, and projecting beyond the inner faces of said plates, and straps or projections forming continuations of said pad and extending along the under edges and projecting beyond the inner faces of said plates and adapted to project under the bottom edges of the plates on the opposite side of the bag when the bag is closed, 60 substantially as described.

In testimony whereof I have hereunto set my hand in presence of two subscribing witnesses.

EDWIN C. JORDAN.
